DESIGN.

J. RITTER.

CLASP DEVICE.

APPLICATION FILED JAN. 10, 1916.

49,445.

Patented July 25, 1916.

Inventor

Jacob Ritter

By his Attorney

Carl P. Sprengel

UNITED STATES PATENT OFFICE.

JACOB RITTER, OF NEW YORK, N. Y.

DESIGN FOR A CLASP DEVICE.

49,445.

Specification for Design.

Patented July 25, 1916.

Application filed January 10, 1916. Serial No. 71,351. Term of patent 3½ years.

To all whom it may concern:

Be it known that I, JACOB RITTER, a citizen of the United States, and a resident of New York, in the borough of Manhattan, county and State of New York, have invented a new, original, and ornamental Design for a Clasp Device, of which the following is a specification, reference being had to the accompanying drawing, forming part thereof.

In the accompanying drawings, the figure shows a front view of the design.

I claim:—

The ornamental design for a clasp device, as shown.

JACOB RITTER.

Witnesses:

F. HOGG,
JOHN SCHWARZ.
